UNITED STATES PATENT OFFICE

92,563

DESIGN FOR A CARTON

John C. Sickel, Chicago, Ill., assignor to Grennan
Bakeries, Inc., Chicago, Ill., a corporation of Illinois

Application April 6, 1934, Serial No. 51,335

Term of patent 7 years

To all whom it may concern:

Be it known that I, JOHN C. SICKEL, a citizen of the United States, residing at Chicago, in the county of Cook, and State of Illinois, have invented a new, original, and ornamental Design for a Carton, of which the following is a specification, reference being had to the accompanying drawing, forming part thereof, and in which;

The single figure is a perspective view showing the new design.

I claim:

The ornamental design for a carton as shown.

JOHN C. SICKEL,
